CLAIM

The ornamental design for an injector pen, as shown and described.

DESCRIPTION

FIG. 1 is a top front perspective view of an injector pen showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the figures show portions of the injector pen that form no part of the claimed design.

The oblique shade lines in the figures show a transparent, reflective, or shiny surface, and not surface ornamentation.

FIGS. 1-7 are illustrated to show contrasting appearance. Areas of the injector pen that appear in different shades of gray represent areas with contrasting appearances. No particular shade or hue is claimed.
